CLAIM

The ornamental design for a container for a toilet plunger or toilet brush, as shown and described.

DESCRIPTION

FIG. 1 is a perspective view of the container for a toilet plunger or toilet brush;

FIG. 2 is a back elevational view thereof;

FIG. 3 is a front elevational view thereof;

FIG. 4 is a right side elevational view thereof, the left side being the mirror image of the right side;

FIG. 5 is a top plan view thereof; and,

FIG. 6 is a bottom plan view thereof.
